DESIGN FOR A REVERSIBLE HOUSECOAT

Michael Koury, New York, N. Y.

Application June 26, 1939, Serial No. 85,698

Term of patent 3½ years

To all whom it may concern:

Be it known that I, Michael Koury, a citizen of Lebanon and resident of New York city, in the county of New York and State of New York, have invented a new, original, and ornamental Design for a Reversible Housecoat, of which the following is a specification, reference being had to the accompanying drawing, forming a part thereof.

Fig. 1 is a front elevational view of a reversible housecoat, showing my new design.

Fig. 2 is a rear elevational view of the same.

Fig. 3 is a similar view to Fig. 1, showing the same in the inside-out condition.

I claim:

The ornamental design for a reversible housecoat, as shown.

MICHAEL KOURY,
